UNITED STATES PATENT OFFICE

169,351

LAUNDRY MACHINE

Melvin H. Boldt, Glenview, Ill., assignor to Avco
Manufacturing Corporation, South Bend, Ind.,
a corporation of Delaware

Application July 28, 1952, Serial No. 20,787

Term of patent 14 years

(Cl. D49—1)

To all whom it may concern:

Be it known that I, Melvin H. Boldt, a citizen of the United States, residing in Glenview, in the county of Cook and State of Illinois, have invented a new, original, and ornamental Design for a Laundry Machine, of which the following is a specification, reference being had to the accompanying drawing, forming part thereof, and wherein the single figure is a perspective view of a laundry machine showing my new design.

I claim:

The ornamental design for a laundry machine, substantially as shown.

MELVIN H. BOLDT.
